UNITED STATES PATENT OFFICE.

CHARLES OTERO, OF PUEBLO, COLORADO.

DESIGN FOR A SPOON.

SPECIFICATION forming part of Design No. 22,557, dated June 27, 1893.

Application filed May 23, 1893. Serial No. 475,277. Term of patent 3½ years.

To all whom it may concern:

Be it known that I, CHARLES OTERO, a citizen of the United States, residing at Pueblo, in the county of Pueblo and State of Colorado, have invented and produced a new and original Design for a Spoon, of which the following is a specification, reference being had to the accompanying drawings, forming a part of this specification, in which—

10 Figure 1 is a plan view of the obverse side of a spoon embodying the features of my design; and Fig. 2 is a plan view of the reverse side of the spoon.

15 The design consists in the handle, which comprises the representation of a hammer symbolical of the Nebraska hammer, a flag draped around the hammer, a nail coupled with the hammer and flag and representative

of the Montana nail, and a medallion decorated with a portrait intended to represent the 20 likeness of a female, the entire handle design being symbolical of woman's work. The obverse side of the bowl of the spoon is decorated with the representation of the Colorado mineral palace casket. The obverse side of 25 the handle also represents a hammer draped with a flag and surmounted by a medallion, the medallion representing upon its surface the Montana State coat of arms.

I claim—

30 The design for a spoon, substantially as herein shown and described.

CHARLES OTERO.
